UNITED STATES PATENT OFFICE.

CLARENCE M. CREWS, OF BROOKLYN, NEW YORK, ASSIGNOR TO UNDERWOOD TYPE-WRITER COMPANY, OF NEW YORK, N. Y., A CORPORATION OF DELAWARE.

TYPEWRITING MACHINE.

Application filed June 7, 1924. Serial No. 718,473.

To all whom it may concern:

Be it known that I, CLARENCE M. CREWS, a citizen of the United States, residing in Brooklyn Borough, in the county of Kings, city and State of New York, have invented certain new and useful Improvements in Typewriting Machines, of which the following is a specification.

This invention relates to continuous billing typewriting machines. In a machine of this class a set of carbons is ordinarily attached to a carbon-carrier which is advanceable toward the platen with an interleaved work-web at line-feeding, and is retractile from the platen and relatively to the interleaved work-web upon displacement of the platen, to strip the carbons from a typed form-section and interleave them with the form-section next to be typed. The carbons are arrested by a stationary rear stop, always in the same rearward position, and hence the type blows at the writing of successive forms fall always in substantially the same locations on the carbons, which causes the carbons to be worn out in stripes, so that they must be removed from the machine and replaced without being used to their utmost capacity. This method of using the carbons is especially wasteful because the carbons are ordinarily quite long. The changing of the carbons in the machine, moreover, is a time consuming operation which it is desirable to postpone and avoid as much as possible.

It is an object of the present invention to provide means for causing the carbons of a continuous billing machine to be worn out uniformly, so that the maximum use, and length of service, may be obtained from the carbons.

To this end provision may be made of means to arrest the retraction of the carbon-carrier in a slightly different location at successive retractions thereof, so that the type blows will be caused to fall upon slightly different portions of the carbon at the writing of the succeeding forms. As illustrated herein the carbon-carrier arresting means may consist of an eccentric cam, and means engaged and actuated by the carbon-carrier in its rearward movement to rotate the cam a short distance. With this arrangement the rear-stopping position of the carbon-carrier is caused automatically to os-

cillate back and forth within a short range, 55 so that the carbons at successive writings are shifted progressively by fractional line-space degrees with reference to the writing line of the machine and so are completely worn out by the ordinary use of the machine. 60

Other features and advantages will hereinafter appear.

In the accompanying drawings, 65 Figure 1 is a sectional side elevation of a portion of a continuous billing machine having the present improvements applied thereto, the machine being cut away at an intermediate portion for compactness of illustration. 70

Figure 2 is a vertical section on a larger scale than Figure 1, taken on the line 2—2 of Figure 1, looking in the direction of the arrows, and showing the details of the stop mechanism. 75

Figure 3 is a detail view of a portion of the stop-feeding means.

Figure 4 is a fragmentary sectional side elevation of the stop-feeding means and carbon-carrier with the carbon-carrier near the rear limit of its movement. 80

Figure 5 is a fragmentary plan view of the mechanism shown in Figure 4.

The illustrated typewriting machine, which is of the type disclosed in the patent 85 to Wernery & Smith, 1,132,055, comprises a revolute cylindrical platen 10 which is journaled by its axle 11 in a displaceable platen-frame 12 mounted upon a carriage 13 that travels in letter-feed and return directions, as usual. A carbon-carrier 14 is mounted to travel toward and from the platen 10 upon rails 15, forming part of a long carriage extension 16 that travels from side to side with the carriage and is supported at 90 its rear upon a rail 17 carried by a rear extension 18 of the machine-frame. A multiple-ply continuous work-web 19 is led into the machine between side guides 20 at the rear extremity of the carriage extension 16, and thence is led forward in interleaved relation with a set of carbons 21 carried by carbon-blades 22 on the carbon-carrier 14. The work-web 19 and carbons 21 are advanced together by the platen 10 in conjunction with co-operating feed-rolls 22 by actuation of the usual line-spacing mechanism (not shown) until the first form is 100 105

fully typed. The platen-frame 12 is then released from its normal position by movement of a latch 23 to the rear, and is thrown up to permit the work-web 19 and carbons 21 to be straightened beneath the platen. The work-web 19 is then drawn forward to a gage 24 carried by a gage-bar 25 at the delivery side of the platen and there held stationary while the carbon-carrier 14 is thrust 10 to the rear by its handle 26 to strip the carbons 21 from the typed web-section and interleave them with the section next to be typed.

Heretofore the stop for limiting the rearward movement of the carbon-carrier has been maintained stationary. According to the present invention provision is made of an eccentric cam stop 27 which is rotatably mounted on a shaft 28 fixed in clamping 20 brackets 29 and 30 adjustably secured upon the left rail 15 of the carriage extension 16 and upon the central longitudinal bar 31 of said extension, respectively. The cam stop 27 is made fast to a ratchet-wheel 32 by means of pins 33 on the ratchet-wheel, and the position of the cam 27 and the ratchet-wheel 32 lengthwise of the shaft 28 is controlled by the bracket 29 and a collar 34 fast on the shaft 28. An oscillatory arm 35 30 plays between shoulders 36 and 37 on the bracket 29, and carries a pawl 38 which is pressed by a spring 39 into co-operative engagement with the ratchet-wheel 32. The carbon-carrier 14 has a rearwardly-projecting arm 40 which engages an upwardly-projecting pawl 41 on the oscillatory arm 35 each time that the carbon-carrier 14 is moved to the rear, to rock the oscillatory arm from the full-line position of Figure 4 40 to the rear dot-and-dash line position 35' to impart a feeding step to the ratchet-wheel 32, and through the ratchet-wheel to the eccentric cam stop 27. The parts are so constructed that the projecting arm 40 leaves engagement with the pawl 41 as seen in dot-and-dash lines in Figure 4 when the ratchet-wheel 32 has been rotated one tooth-space. The oscillatory arm 35 is thereupon returned to its normal full-line position by a spring 50 42. The rearward movement of the carbon-carrier 14 is finally arrested by engagement of a projection 43 on the carbon-carrier with the front face of the eccentric cam 27. As the position of the cam 27 varies continually, 55 due to this progressive feeding, the rear limit of the carbon-carrier's movement is correspondingly varied, so that slightly different portions of the carbons 21 are made effective for each form typed.

60 The pawl 41 is normally held upright and rigid against a shoulder 44 on the oscillatory arm 35 by a spring 45. At the forward movement of the carbon-carrier 14 this spring 45, with the pawl 41, is turned down 65 to the dot-and-dash line position 41' of Fig-

ure 4 by the arm 40, permitting said arm to pass.

It will be understood that for a half revolution of the cam stop 27 the carbon-carrier 14 is arrested progressively farther to the rear, and that for the next half revolution it is arrested progressively farther forward. In other words, the arresting position oscillates backward and forward. The extent of this oscillation may be slightly less than a double line-space, so that in case the machine is set for double line-spacing the zone within which the first-line type blows fall on the carbons will touch, but will not overlap the zone within which the second-line type blows fall. This variation will not prevent the use of the carbons as near to the tops of the forms as desired, because the forms have printed headings which occupy a considerable space at their upper margins. At the same time this amount of variation may be had without danger of the carbons being severed at their forward ends with the work-web, by the knife 46. The cam is preferably contoured to cause the carbons to progress by uniform steps, so that every portion will receive exactly the same amount of wear.

Variations may be resorted to within the scope of the invention, and portions of the improvements may be used without others.

Having thus described my invention, I claim:

1. In a continuous billing typewriting machine, the combination with a revoluble platen and a carbon-carrier retractible from the platen to reposition the carbons with reference to the work-web and the platen, of means operated automatically by the movement of the carbon-carrier to arrest the carbon-carrier in slightly different position at each retraction thereof.

2. In a continuous billing typewriting machine, the combination with a revoluble platen and a carbon-carrier retractible from the platen to reposition the carbons with reference to the work-web and the platen, of an adjustable stop to limit the rearward movement of the carbon-carrier, and means dependent upon the operation of said carbon-carrier for automatically adjusting the stop.

3. In a continuous billing typewriting machine, the combination with a revoluble platen and a carbon-carrier retractible from the platen to reposition the carbons with reference to the work-web and the platen, of means automatically to cause the carbons to be oscillated slowly by fractional line-space degrees with reference to the writing line throughout an extended period of operations.

4. In a continuous billing typewriter machine, the combination with a revoluble platen and a carbon-carrier retractible from the platen to reposition the carbons, of ad-

justable means to arrest the retraction of the carbon-carrier and thereby control the position of the carbons with reference to the line of writing, and means actuated by the retraction of the carbon-carrier to adjust automatically the carbon-carrier arresting means.

5. In a continuous billing typewriting machine, the combination with a revoluble 10 platen and a carbon-carrier retractible from the platen to reposition the carbons with reference to the work-web, of an eccentric rotatable cam stop in the path of the carbon-carrier, and means actuated by the carbon-carrier in its rearward movement to rotate the cam to bring different portions of its surface into position to intercept the carbon-carrier.

6. In a continuous billing typewriting machine, the combination with a revoluble 20 platen and a carbon-carrier retractible from the platen to reposition the carbons with reference to the work-web and the platen, of an eccentric rotatable cam stop in the 25 path of the carbon-carrier, a ratchet-wheel fast to the cam, a pawl for feeding the ratchet-wheel step by step, and means carried by the carbon-carrier to actuate the pawl at each rearward movement of the carbon-carrier.

7. In a continuous billing typewriting machine, the combination with a revoluble 30 platen and a carbon-carrier retractible from the platen to reposition the carbons with reference to the work-web and the platen, of an eccentric rotatable cam stop in the path of the carbon-carrier, a ratchet-wheel fast 35

to the cam, a pawl for feeding the ratchet-wheel step by step, a pawl-carrying arm, a projection on the carbon-carrier for engaging and actuating the pawl-carrying arm to feed the ratchet-wheel a tooth space in the course of the carbon-carrier retracting movement but not in the last portion thereof, and means enabling the projection on the carbon-carrier to pass the pawl-carrying arm in 40 the forward movement of the carbon-carrier. 45

8. In a continuous billing typewriting machine, the combination with a traveling 50 carriage and a carriage-extension, of a revoluble platen, a carbon-carrier retractible from the platen to reposition the carbons with reference to the work-web and the platen, an eccentric rotatable cam stop in the path of the carbon-carrier, a shaft on 55 which the cam stop is mounted, and clamping brackets for adjustably securing the shaft in various locations upon the carriage-extension.

9. In a continuous billing typewriting machine, the combination with a revoluble 60 platen, a carriage, a carriage-extension and a carbon-carrier retractible from the platen along the carriage-extension to reposition the carbons with reference to the work-web 65 and the platen, of a carbon-carrier stop, means for feeding said stop to adjust it automatically at every retracting movement of the carbon-carrier, and means for adjusting the stop and its feeding means to 70 various positions upon the carriage-extension. 75
